UNITED STATES PATENT OFFICE.

JULES SIMON AND PAUL FRANÇOIS SARRON, OF LYON, FRANCE.

ELECTRIC RESISTANCE-FURNACE.

1,334,809.

Specification of Letters Patent. Patented Mar. 23, 1920.

Application filed November 18, 1918. Serial No. 262,356.

To all whom it may concern:

Be it known that we, JULES SIMON, of Lyon, France, and PAUL FRANÇOIS SARRON, of Lyon, France, citizens of the French Republic, have invented a certain new and useful Improvement in Electric Resistance-Furnaces, of which the following is a specification.

The invention relates to apparatus for producing in general changes of physical condition or endothermic chemical reactions used in industry, such being effected by means of a continuous circulation of hot gases forming a cycle, the gases being heated by means of an electric furnace. Examples of the application of the invention to an electric blast furnace, to a furnace for calcining carbonates, and to a gas generator employing the carbonic acid of the carbonates, will be hereinafter described.

In the process of operating the improved furnace the provision of the necessary calories is effected by means of a suitable gas or gaseous mixture, which we call "the cyclic gas," which gas is previously brought to the desired temperature, and which, after having transmitted its heat to the materials to be treated, is again heated, and employed for a fresh addition of calories to the materials, this cycle of operations being indefinitely repeated. In the case where the treatment of the materials causes the disengagement of a gas, the latter mixes with the cyclic gas, and the volume of gas thus obtained is collected at its issue from the furnace, the amount of gas which is to be again used in the cycle is abstracted and the remaining gas is available for any use.

In the accompanying drawing Figures 1 and 2 represent a portion of a blast furnace, which is of similar construction to a blast furnace heated with coke or charcoal, and a group of electric gas heaters associated therewith.

Fig. 1 is a vertical section through line 1-1 of Fig. 2, and shows the crucible, the tuyers and a resistance furnace for heating the cyclic gas.

Fig. 2 is a horizontal section on line 2-2 of Fig. 1.

Figs. 3 and 4 show a furnace for calcining carbonates.

Fig. 3 is a sectional elevation on the line 3-3 of Fig. 4, and

Fig. 4 is a section on the line 4-4 of Fig. 3.

In the apparatus shown in Figs. 1 and 2 the tuyers 5 are of a special type, because they are to inject a gas at a temperature of about 1,800° C., while in the ordinary blast furnaces, the air injected is only at a temperature of 700° or 800° C. The metal part 6 is similar to that of the ordinary blast furnace tuyers, but they have an orifice of greater diameter, allowing the introduction of a highly refractory protecting lining 7 made of a material such as carborundum or cast quartz. The metal part being cooled in the usual manner, this lining is itself somewhat cooled, which insures its lasting a long time. These tuyers are each provided with a flange 8, keyed on the flange 9 of the tube 10 of the resistance furnace 11. This furnace is formed of an outer metal shell 12 inside which is a refractory lining 13 this lining is itself lined with a further and more refractory lining 14, which is also a bad conductor of electricity. Inside this inner lining, and resting on the arch 15, is a structure formed of a highly refractory material and graphite, and capable of being strongly heated by the passage of an electric current conducted by the electrodes 16, and passing through the walls of the various linings and the metal shell. In this structure are channels 17 produced by casting at the time of its manufacture, and connecting the upper chamber 18 and the lower chamber 19 through the arch 15: the latter chamber is connected, by means of the pipe 20, to the conduit 21, the pipe 22 of which is provided with a suitable sliding valve 23. The whole installation also comprises, as in the ordinary blast furnaces, a blower, gas-inlets at the furnace top, apparatuses for purifying the gases and suitable recuperators.

The working of this electrical furnace is similar to that of the ordinary blast furnaces the loading of the materials is effected in the same manner, but the amount of carbon introduced into the same is only that required for the reduction of the oxids and of a part of the carbonic acid, since the heat required for the various reactions and for the fusion of the dross is supplied by the cyclic gas. The latter, coming from the recuperators through the conduit 21, passes

into the chamber 19, then circulates in the channels 17, where it is brought to the required temperature, passes into the chamber 18 and then passes into the crucible 24. After having in its rising course transferred its calories to the materials to be treated, while causing the usual reactions and alterations of physical condition, it reaches the furnace-top mixed with the gas arising from the reactions: the gaseous mass thus formed then passes through the purifying apparatuses, and the amount of gas constituting the cyclic gas is then sucked out by the ventilator and driven back into the recuperators, which have been previously heated by the combustion of the gas arising from previous reactions the burnt gases being collected while still hot in order to serve for dessicating the materials which are to compose the charge. The quantity of calories discharged by the combustion of the gas from the reactions can be more or less increased by enriching this gas by means of gas or fuels of high calorific capacity (gases from coking ovens, heavy oils, petrolierous products, etc.). In this case the refractory masonry of the recuperators is constructed for resisting the temperatures required to be reached. By this method, the cyclic gas can be brought to a very high temperature, which allows of expending less electric energy in the superheaters. In all cases, in view of producing a rapid superheating of the cyclic gas, the superheaters are brought to a temperature distinctly higher than that which the gas is to have when it passes into the crucible.

The principal advantages obtained by this electric furnace are as follows:—

- 40 (a) Consumption of carbon reduced to that necessary for the reduction of the ore and a portion of the carbonic acid.
- 45 (b) Consumption of electric energy less than that of the known electric blast furnaces, owing to the utilization of the gas from the reactions.
- 50 (c) Possibility of treating large quantities of ore as in ordinary blast furnaces.
- 55 (d) Practically complete absence of nitrogen in the cyclic gas and in the gas recuperated.
- 60 (e) Omission of the electrodes, used in the interior of almost all known electric blast furnaces, and consequently of the defects which they produce, such as zones of excessive temperature, contact with the materials to be treated, enormous consumption, etc.
- 65 (f) Complete independence of the blast furnace proper from the electric apparatus, allowing an ordinary blast furnace to be easily transformed into an electric blast furnace by the simple addition of superheaters and special twyrs.
- 70 (g) Constitution of the fusion bed as in

ordinary blast furnaces, that is to say, without previous mechanical treatment of the materials, the latter not requiring the electric current to pass through them.

(h) Easy regulation of the working of the furnace by acting on the intensity of the current in the superheaters or on the speed of the cyclic gas.

(i) Possibility of correcting, according to requirements, the composition of the cyclic gas, by insulating with the latter carbonated products capable of increasing the reducing power of the gas.

In the apparatus shown in Figs. 3 and 4, for calcining carbonates, the material to be treated is fed into the furnace *a* by means of the known "cup and cone" device *b*, which provides air-tightness of the furnace at its upper part.

This air-tightness is secured in the lower part by means of the door *c* arranged below the grating *d*. The cyclic gas, sucked in by the suction pump *e*, passes into the conduit *f*, then into the partitioned recuperator *g*, arranged so as to absorb the greater part of the calories which the calcined materials possess: the gas is heated in passing through it, and passes through the pipes *h* level with which are tubes of smelted quartz *i* embedded in a mass of pulverulent substance *j*, composed of graphite and carborundum and maintained at the suitable temperature by the passage of an electric current from the electrodes *k* and *l*. After having passed through the tubes *i*, the cyclic gas passes into the chamber *m*, then reascends, through the smelted quartz tubes *n*, where its heating is completed.

The whole device is designed so that the gas may have the desired temperature when it passes through the collectors *o* and enters the furnace through the pipes *p*, where it meets in its ascent the carbonate to be decomposed; the gaseous mass is then increased by the carbonic acid proceeding from the decomposition of this carbonate, and is collected at the furnace-top *q*, by the suction pipe *r*, which conveys it to the filter *s*, where the dust gathered is deposited. The height of the furnace, from the twyrs to the top is that which allows the best utilization of the calories supplied by the cyclic gas. The whole gaseous mass is sucked from the filter *s* by the suction apparatus *e*: the amount of gas which is to return in the cycle passes into the conduit *f*: the excess of available gas passes through the pipe *t* provided with a regulating valve *u* and passes to a gas receiver not illustrated, which is kept constantly in suction. There it is collected for the industrial use contemplated.

The calcined materials descend gradually at each draw and surround the regenerator *g*, to which they yield the greater part of

the calories that they possess, so that, when they arrive in the hopper carrying the grating *d*, they are nearly cooled. The drawings are made as frequently as possible, taking care to stop the arrival of the cyclic gas during these operations, in order to prevent reentrance of air, which would introduce nitrogen into the gaseous current. If it is desired to dispense with regenerating the calories possessed by the calcined product, the regenerator can be omitted, and the height of the lower part of the furnace diminished.

The principal advantages presented by this process are as follows:—

- (a) As the furnace does not contain solid fuel, there are no cinders, whereby a very pure product may be obtained, and caking is avoided.
- (b) Recuperation of carbonic acid capable of being employed for any industrial use, after having, or not having, been freed from the vapor which it may contain.
- (c) Great care in regulating the temperature of the furnace enabling a regular action to be obtained.

(d) The gaseous movement, due to the suction produced in the furnace, facilitates the disengagement of the carbonic acid from the carbonates, the tension of dissociation being much less than that which would produce the re-combination of the carbonic acid with the lime.

The process is also applicable to a type of gas generator constructed and working in the same manner as the calcining furnace above described. However, the charges, instead of being only composed of the carbonate to be treated, comprise successive layers of carbonates and of carbonated products (any combustible bodies, even of bad quality, etc.) The gas arising from the reactions started by the calorific addition of the cyclic gas, is then a mixture of carbonic acid, carbon monoxid, and also of hydrocarbons, if the carbonated product employed contains the same. As in the preceding cases, the quantity of gas necessary for the cycle is previously abstracted from the gaseous mass obtained and brought in electric heating apparatuses similar to those previ-

ously described, to the most suitable temperature for obtaining the best ratio $\text{CO}_2 : \text{CO}$.

The advantages presented by this gas generator are as follows:

- (a) Utilization of a portion of the carbon of the carbonic acid of the carbonates.
- (b) Utilization of a large number of carbonated products hitherto difficult or even impossible to utilize industrially (bad fuel, waste, etc.)
- (c) Production of a combustible gas free from nitrogen.

What we claim as our invention and desire to secure by Letters Patent of the United States is:—

1. In apparatus for the purpose set forth the combination of a furnace chamber, a gas heating chamber having a gas inlet, a twyer connecting said gas heating chamber to said furnace chamber, tubes of cast quartz in said gas heating chamber in the path of the gas between said inlet and said twyer, a pulverulent electric resistance incasing said tubes and composed of carborundum and graphite, and electrodes for passing electric current through said resistance.

2. In apparatus for the purpose set forth the combination of an air-tight furnace chamber, a heat recuperator at the base of said chamber, means for admitting gas to said recuperator, a gas heating chamber, means for conducting gas from said recuperator to said heating chamber, tubes of cast quartz in said gas heating chamber, in the path of the gas, a pulverulent electric resistance incasing said tubes and composed of carborundum and graphite, electrodes for passing electric current through said resistance, a gas filter, and gas conduits connecting said filter to said recuperator and to the upper part of said furnace chamber respectively.

In witness whereof we have signed this specification in the presence of two witnesses.
